SAFETY CATCH

Raymond L. Wells, Attleboro, Mass., assignor to
 Wells Manufacturing Company, Attleboro,
 Mass., a corporation of Massachusetts

Application November 7, 1935, Serial No. 48,707

4 Claims. (Cl. 24—157)

This invention relates to improvements in safety retaining clasps or catches for use with pin stems and the like.

One of the principal objects of the invention is to provide an improved safety retaining clasp or catch for use with pin stems and the like.

Another object is to provide an improved automatically operating safety retaining clasp or catch for use with pin stems and the like that will temporarily lock the stem in place when it is pushed into the clasp or catch and which has additional means which may be manually rotated to permanently lock the stem in said clasp or catch whereby rotary movement of the permanent lock means in a direction opposite to its locking movement will cause the stem to be ejected from the clasp or catch.

Another object is to provide a simple, efficient and inexpensive safety clasp or catch having a novel double lock arrangement wherein one of said locks operates automatically and the other operates manually.

Another object is to provide an improved guard for the end of the pin stem.

Another object is to provide a clasp or catch which has a wide variety of uses and which is provided with means by which it may be quickly and easily secured to the means with which it is to be used.

Other objects and advantages of the invention will become apparent from the following description taken in connection with the accompanying drawing, and it will be apparent that many changes may be made in the details of construction and arrangements of parts shown and described without departing from the spirit of the invention as set forth in the accompanying claims, I, therefore, do not wish to be limited to the exact details of construction shown and described as the preferred forms only have been shown and described by way of illustration.

Referring to the drawing:

Fig. I is an enlarged perspective view of the clasp or catch embodying the invention, showing it applied to a bar type breast pin and with the parts of the clasp or catch opened out to show their construction;

Fig. II is an enlarged fragmentary sectional view of clasp or catch embodying the invention, showing the parts thereof in assembled relation and secured to the bar pin;

Fig. III is an enlarged sectional view taken on line III—III of Fig. II, showing the pin entering the safety clasp or catch;

Fig. IV is a view similar to Fig. III showing

the pin pushed into the clasp or catch and showing the automatically functioning emergency lock portion moved over to locked position;

Fig. V is a view similar to Fig. II, showing the permanent locking portion moved into position; 5

Fig. VI is a view similar to Fig. III showing a modified form of the invention.

Some attempts have been made in the past to provide a self locking catch with manually operable lock means for positively locking the stem 10 in the catch, but due to the particular type of keeper used with such catches much difficulty was encountered when it was desired to remove the pin stem from the catch. This was due mainly to the fact that when the keeper was 15 turned in the direction of unlocking it would bind with the stem and in most instances unless the keeper was then carefully moved back and forth in the catch it would prevent removal of the stem. This procedure required the use of 20 both hands and was very annoying and troublesome to the user.

It, therefore, is one of the primary objects of this invention to overcome such difficulties by providing simple and inexpensive means and 25 method of making a catch which upon movement of the keeper in the direction of unlocking will automatically eject the pin stem from the catch.

Referring more particularly to the drawing 30 wherein like reference characters indicate like parts throughout the several views, the device embodying the invention is shown in Fig. I applied to an ordinary bar type pin comprising a plate 1 having a hinge member 2 secured thereto 35 by solder or other suitable means. The hinge member 2 has a pin stem 3 pivotally attached thereto as indicated at 4. The hinge has an enlarged integral base formed, as shown in Fig. I, by folding the metal from which the hinge is 40 formed upon itself to provide protruding flanges 5. This provides a large bottom surface for connection with the plate 1.

The clasp or catch embodying the invention comprises a housing 6 having a keeper member 45 7 rotatably supported therein. The housing has an enlarged integral base 8 formed, as shown in Figures I and II, by folding the metal from which the catch is formed upon itself to provide integral protruding flanges 9 which are secured 50 to the plate 1 by solder or other suitable means.

The housing 6 comprises an upright 10 formed with a hollow cup type bearing end portion 11 in which a guide track 12 formed on the keeper 7 is rotatably mounted. The keeper is held in 55

the cup type bearing by a spaced upright 13. The portion 11 and upright 13 have entrant slots 14 and 15 formed therein to provide entrant means for the pin stem 3 into the keeper 7. 5 In addition to forming bearing means the portion 11 provides guard means for the pointed end 16 of the stem 3.

The keeper, as shown in Figures III, IV and V, has an entrant opening or mouth portion 17, a cam surface 18, a curved slot 19 internally thereof and a hook-like portion 20 adjacent the mouth 17. When the mouth portion 17 is aligned with the slot 15 to receive the pin stem 3, as shown in Fig. III, the cam surface 18 lies at 10 an angle to the longitudinal axis of the slot 15 so that when the pin stem 3 is pressed into the slot 15 it will wedge between the side wall of the slot 15 and cam surface 18 and force the keeper 7 to rotate to the position shown in 15 Fig. IV wherein the hook-like portion 20 will be moved transversely of the slot 15 and automatically lock the pin stem 3 in the catch. The catch is then manually rotated by means of the handle 21 to cause the slotted portion 19 to move 20 about the pin stem, as shown in Fig. V, and cause a solid wall portion 22 of the keeper 7 to be located transversely of the slot 15. This provides positive and more or less permanent 25 lock means for securing the stem in the catch. 30 It is specifically pointed out that the cam portion 18 extends inwardly of the keeper 7 to a point substantially at the effective center of rotation 23 of said keeper and that the slot 15 also extends inwardly to substantially the same 35 point. This provides positive stop means for limiting the movement of the pin stem 3 inwardly of the keeper 7 and prevents its being moved below the cam surface 18. This arrangement provides means, which when the keeper is 40 moved in a direction opposite its locking movement, as indicated by the arrows 24, whereby the cam surface 18 will move into engagement with the lower or under surface of the pin stem 3 and through its under pressure with the stem 45 and through the wedging action of the stem against the side wall of the slot 15 will cause the said stem to be automatically ejected from the catch.

In Fig. VI there is shown a modified form 50 of the invention wherein the housing 33 is provided with an entrant slot 34 at the side thereof instead of along its vertical axis as shown in Fig. III. The remaining details of construction are substantially the same as the construction 55 shown in Fig. III, only in this instance the keeper 35 is provided with a projection 36 with which the pin stem 37 engages when it is forced down the side of the housing towards the entrant slot 34. This rotates the keeper 35 and 60 aligns its entrant mouth 38 with the slot 34 to receive the stem.

The function of the catch from this point on is the same as that of the construction shown in Fig. III.

65 It is again pointed out that the success of the present device is due primarily to the unique structure of the keeper 7 and its cooperative relation with the keeper housing and the entrant slots in said housing.

70 For a more specific study of some of the salient features of the present device, reference is made to Fig. III, wherein it is specifically pointed out that the entrant slot 15 is formed in the housing 6 so that its longitudinal axis 56 extends 75 through the geometrical center of the bearing

portion of the cup 11, and through the effective center of rotation of the keeper 7 as indicated at 23. It is also pointed out that the length of the slot 15 is limited so that its innermost point extends substantially to said effective center 23.

When the keeper is positioned in the housing to receive the pin stem, as shown in Fig. III, the cam surface 18 extends inwardly of the slot 15 at an angle 57 relative to the longitudinal 10 axis 56 of the slot. The said cam surface 18 extends substantially to the point 23 and is adapted to remain in substantially radial relation with the said point 23 when the keeper 7 is rotated in the housing. This radial relation 15 is constant regardless of the position of rotation of the keeper, and insures that the cam 18 will move the hook end 20 of the keeper 7 transversely of the slot 15, as shown in Fig. IV, when the pin stem is pressed into the catch, and also 20 insures that the cam 18 will move inwardly of the slot 15 at the lowermost point 23 of said slot when the keeper is moved backward or in the direction indicated by the arrows 24. This backward movement causes the cam surface 18 25 to engage the stem or bar 3 on the under side thereof, wherein continued backward movement of the keeper will cause the said cam to force the stem or bar 3 outwardly of the slot 15. The internal slot 19 is formed to such a curvature 30 that when the stem 3 is in the catch the keeper may be manually moved to bring the solid wall portion 22 transversely of the slot 15 without hindrance from the stem. The curved edge 58 35 of the slot 19 is carefully blended into the hook portion 20 adjacent one end and into a pocket portion 59 adjacent its opposite end to provide smooth operation. The pocket portion 59 is so formed that it arches over the pin stem and forms positive means for retaining the said stem 40 in the catch.

A stop face 60 is formed on the handle 21 to insure that the mouth portion 17 of the keeper properly aligns with the slot 15 when the keeper is rotated in the direction of unlocking. 45

From the foregoing it will be seen that I have provided simple, efficient, and inexpensive means and method of obtaining all of the objects and advantages of the invention.

Having described my invention, I claim: 50

1. In a device of the character described for use with a pin-like member, a support having a keeper rotatably mounted thereon, said keeper having a substantially J-shaped channel with the walls defining said channel located outside of 55 the center or axis of rotation of said keeper, said support having an entrant slot defined by a U-shaped wall with the bight of the U located in substantial alignment with the center or axis of rotation of the keeper, said J-shaped channel 60 having a mouth portion movable into and out of alignment with the entrant slot in the support with one of the side walls of said mouth portion having a cam surface lying in a plane which terminates in a slightly curved portion substantially at the center of rotation of the keeper and communicating with a locking recess portion having a wall extending in an arcuate contour substantially radially from the axis of the keeper and defining the tip of the J-shaped channel, said keeper being mounted to rotate and lock the end 65 of the pin-like member in closed position in said device when said keeper is moved in one direction and to eject the pin-like member when rotated 70 in the opposite direction. 75

2. In a device of the character described for use with a pin-like member, a support having a circular guideway and a U-shaped slot extending inwardly thereof, a keeper mounted for rotation 5 on said guideway and having a substantially J-shaped channel therein with the walls defining said channel located outside of the center or axis of rotation of said keeper, the bight of the U-shaped slot in said support being located in substantial alignment with the center or axis of 10 rotation of the keeper, said J-shaped channel having a mouth portion movable into and out of alignment with the U-shaped slot in the support with one of the side walls of said mouth portion having a cam surface lying in a plane which terminates in a slightly curved portion 15 substantially at the center of rotation of the keeper and communicating with a locking recess portion having a wall extending in an arcuate contour substantially radially from the axis of the keeper and defining the tip of the J-shaped channel, said keeper being mounted to rotate and lock the end of the pin-like member in closed position in said device when said keeper is moved in one direction and to eject the pin-like member when rotated 20 in the opposite direction.
3. In a device of the character described for use with a pin-like member, a support having a cup-like bearing portion and a portion having a U-shaped slot therein, a keeper having a portion 25 mounted for rotation substantially concentrically of said bearing and having a substantially J-shaped channel therein with the walls defining said channel located outside of the center or axis of rotation of said keeper, the bight of the U-shaped slot being located in substantial alignment with the center or axis of rotation of the keeper, said J-shaped channel having a mouth portion movable into and out of alignment with 30 the slot in the support with one of the side walls of said mouth portion having a cam surface lying 35
- in a plane which terminates substantially at the center of rotation of the keeper and communicating with a locking recess portion having a wall extending in an arcuate contour substantially radially from the axis of the keeper and defining the tip of the J-shaped channel, said keeper being mounted to rotate and lock the end of the pin-like member in closed position in said device when said keeper is moved in one direction and to eject the pin-like member when rotated 40 in the opposite direction.
4. In a device of the character described for use with a pin-like member, a member having spaced supporting portions, one of said portions having a circular guideway, and the other a U-shaped slot with the bight of the slot located in substantial alignment with the center of the circular guideway, a keeper positioned between said spaced supporting portions having an integral projection rotatably supported in the guideway 20 and having a substantially J-shaped channel therein with the walls defining said channel located outside of the center or axis of rotation of said keeper, said J-shaped channel having a mouth portion movable into and out of alignment with the U-shaped slot in the support with one of the side walls of said mouth portion having a cam surface lying in a plane which terminates substantially at the center of rotation of the keeper and communicating with a locking 25 recess portion having a wall extending in an arcuate contour substantially radially from the axis of the keeper and defining the tip of the J-shaped channel, said keeper being mounted to rotate and lock the end of the pin-like member 30 in closed position in said device when the said keeper is moved in one direction and to eject the pin-like member when rotated in the opposite direction.

40 RAYMOND L. WELLS.
